Primary Examiner — Ricky Pham(74) *Attorney, Agent, or Firm* — Carter, DeLuca, Farrell & Schmidt LLP(57) **CLAIM**

The ornamental design for a cooking tray, as shown and described.

DESCRIPTION

FIG. 1 is a perspective view of a cooking tray in accordance with the present design;

FIG. 2 is a right side elevational view thereof, the left side elevational view being a mirror image thereof;

FIG. 3 is a front side elevational view thereof, the rear side elevational view being a mirror image thereof;

FIG. 4 is a top plan view thereof; and,

FIG. 5 is a bottom view thereof.

The broken lines shown are included for the purpose of illustrating a portion of the cooking tray that forms no part of the claimed design.

The stippling in the drawings is for shading purposes only.

1 Claim, 4 Drawing Sheets(56)
